UNITED STATES PATENT OFFICE.

PAUL MOEWS, OF DETROIT, MICHIGAN, ASSIGNOR TO THE MICHIGAN OPTICAL COMPANY, OF SAME PLACE.

FITTING FOR EYEGLASSES OR SPECTACLES.

SPECIFICATION forming part of Letters Patent No. 674,448, dated May 21, 1901.

Application filed August 27, 1900. Serial No. 28,190. (No model.)

To all whom it may concern:

Be it known that I, PAUL MOEWS, a citizen of the United States, residing at Detroit, in the county of Wayne and State of Michigan, have invented certain new and useful Improvements in Fittings for Eyeglasses or Spectacles, of which the following is a specification, reference being had therein to the accompanying drawings.

10 The invention relates to frameless eyeglasses, and more particularly to the fitting employed for attaching the lens to the bridge.

It is the object of the invention to obtain a simple construction of fitting which may be formed from a single piece of sheet metal; further, to prevent danger of breaking the lens in securing the fitting thereto, and, further to provide means of attachment to lenses of varying thickness.

20 The invention consists in the peculiar construction of the fitting in which one of the ears for embracing the lens is attached to the body of the fitting by a connection which in turn forms an edge brace for the lens, thereby dispensing with an extra part and at the same time securing a flexible connection for the ear.

The invention further consists in the peculiar construction of said fitting from the single sheet-metal blank, and, further, in the peculiar construction, arrangement, and combination of parts, as hereinafter described and claimed.

In the drawings, Figure 1 shows an elevation of a portion of a spectacle-frame in which the fitting is used. Fig. 2 is a plan view of Fig. 1. Fig. 3 is a perspective view of the fitting detached. Fig. 4 is a plan of the blank of which the fitting is formed. Fig. 5 is a 40 cross-section of line $\alpha\alpha$ of Fig. 1. Fig. 6 is a perspective view showing a modification.

Although I have shown my invention as applied to a spectacle-frame, it is obvious that it is equally applicable to other frames of eyeglasses.

As shown in the drawings, A designates the bridge of a frame, B one of the lenses, and C the fitting for securing the lens to the bridge. This fitting is preferably formed 50 from a sheet-metal blank, as shown in Fig. 4, having a body portion a and the ears b and

c , the latter ear being connected to the body by the narrow strip d . When completely formed, the ear b is bent at right angles to the body portion a and the strip d is bent 55 into a loop or a return-bend, so as to bring the ear c into a plane parallel with the ear b , as shown in Figs. 2 and 3. The loop d is so arranged as to form one of the edge braces for the lens, while the opposite edge brace is 60 formed by an extension e of the body. The body a may be soldered or otherwise secured to the bridge A or to any other part of the frame, according to the particular construction of the latter. When thus secured, the 65 fitting C forms a clip for attaching the lens, the ear b passing on one side thereof and the ear c on the opposite side, while the screw f , passing through said ears and a corresponding aperture in the lens, serves to clamp the 70 parts together. The ear b being rigid is preferably placed on the inner face of the lens in order to hold said face a fixed distance from the eye, while the ear c , being carried by the flexible loop, is free to adjust itself to varying 75 thicknesses of lens. In order to prevent breakage of the lens, I preferably coat the inner faces of the ears a and b with a lining of soft metal which is sufficiently yielding in its nature to permit of forming a true bearing on 80 the lens when the ears are clamped by the screw. This will distribute the pressure upon the glass, and consequently avoid fracture.

In Fig. 6 is shown a modification in which the ear c is attached to the body by a double 85 loop $d^1 d^2$, which loops form the opposite edge braces for the lens.

The construction of fitting above described is exceedingly simple and inexpensive to manufacture. Moreover, the placing of the 90 loop d adjacent to the edge of the lens is a much more compact and neater arrangement than constructions heretofore made.

What I claim as my invention is—

1. In spectacles or eyeglasses, the combination of the lens, and a fitting therefor comprising a body portion, an ear secured to the lens, and a connection between the body and ear projecting from one side of the body a considerable distance in substantially the 100 plane of the lens and bearing against the edge of the latter forming the lens-brace.

2. In spectacles or eyeglasses, the combination of the lens, and a fitting therefor, comprising a body portion, an ear secured to the lens, and a flexible connection between the body and ear extending from the former in substantially the plane of the lens and bearing against the edge of the latter at one side of the body, forming a lens-brace.

3. In spectacles or eyeglasses, the combination of a lens, and a fitting therefor comprising a body portion, an ear secured to the lens, and an elongated loop, connecting the body and ear, extending from the former in substantially the plane of the lens and bearing against the lens edge at one side of the body forming the lens-brace.

4. In spectacles or eyeglasses, the combina-

tion of a lens, and a fitting therefor constructed from a single blank of sheet metal, comprising a body portion and laterally-extending ear, a narrow flexible strip connected at one end to the body and bent to form an elongated loop projecting at some distance from said body in the plane of the lens and curved to conform to the lens edge, and a second ear, 25 carried by the free end of the loop, lying in a plane parallel to the other ear.

In testimony whereof I affix my signature in presence of two witnesses.

PAUL MOEWS.
